UNITED STATES PATENT OFFICE.

ANTON SCHUERMANN, OF DECATUR, ILLINOIS, ASSIGNOR OF ONE-HALF
TO H. MUELLER MANUFACTURING COMPANY, OF DECATUR, ILLINOIS,
A CORPORATION OF ILLINOIS.

SCREW-CUTTING LATHE.

No. 806,996.

Specification of Letters Patent.

Patented Dec. 12, 1905.

Application filed June 10, 1905. Serial No. 264,724.

To all whom it may concern:

Be it known that I, ANTON SCHUERMANN, of the city of Decatur, county of Macon, and State of Illinois, have invented certain new and useful Improvements in Screw-Cutting Lathes, of which the following is a specification.

The object of this invention is to provide means whereby the thread-cutting tool may be moved slightly faster or slightly slower than the regular motion of the tool-rest, so that the lathe may be used for either inch measure or metric measure and so that shrinkage of cut threads through tempering or otherwise may be compensated for or anticipated. For instance, a tap intended to cut threads of a certain pitch may be threaded by my machine to the slightly increased pitch needed to neutralize or compensate for the shrinkage resulting from subsequent tempering, or bolts or the like may be threaded to the slightly-reduced pitch needed to conform to holes threaded by taps the threads of which have been shrunk from regular size by tempering.

The mechanism herein described may be applicable to purposes not specifically stated, and it is my desire to patent the invention for all purposes to which it may be applied.

The invention is exemplified in the structure hereinafter described, and it is defined in the appended claims.

In the drawings forming part of this specification, Figure 1 is an elevation of so much of a screw-cutting lathe as is needed to show the relation of my invention thereto. Fig. 2 is a plan of the mechanism shown in Fig. 1. Fig. 3 is a side elevation of an embodiment of my invention detached from the lathe-carriage. Figs. 4 and 5 are plan details of certain parts of my machine, showing how the motion that retards or accelerates the cutting-tool is developed by travel of the slide-rest through inclined-plane action. Fig. 6 is a detail plan of the slotted bar and adjuncts used in developing the variable-speed movement. Fig. 7 is a plan of the under surface of that part of the slide-rest that is accelerated or delayed to vary the pitch of the threads. Fig. 8 is a detail of the elements that coat with the slotted bar to develop the variable motion in the cutting-tool. Fig. 9 is a detail of the under surface of the dial-

plate, which receives motion from the slotted bar through the elements shown in Fig. 8 and 55 imparts it to the tool-carrying part of the slide-rest. Figs. 10 and 11 are plans of my invention, illustrating the action thereof. Fig. 12 is a plan of the upper element of the slide-rest with the dial-plate in place. Fig. 60 13 is a similar plan with the dial-plate removed. Fig. 14 is a section on line X in Fig. 13. Fig. 15 is a section on line X in Fig. 12. Fig. 16 is a detail in elevation of the dial-plate and the parts that coat most intimately therewith.

A slide-rest is formed in two parts 14 and 18. The part 14 is secured to the cross-slide 20 of a tool-carriage of a screw-cutting lathe by bolts extending through holes 15, and it occupies the same position as a compound swivel-rest. A bar 19 is secured to the tailstock 21 of the lathe, and it extends horizontally crosswise of the lathe, with an edge presented upward. A flat bar 1 is grooved 75 crosswise at one end in its under surface to engage bar 19, as shown in Fig. 1, and it has the oblique groove 2 in its upper surface. A key 3 fits slidably in groove 2. A plate 4 is formed on the upper surface of the key crosswise thereof, and a pivot-pin 5 extends upward from the center of plate 4. A slide-key 6 is pivoted on pin 5, and it moves in groove 8 of the lower member of the dial-plate. The part 14 of the slide-rest has the gib 14^a, which 80 fits slidably in the dovetail groove 18^a of part 18 of the slide-rest, and the grooved bar 1 extends slidably lengthwise through the gib. A pair of cover-plates 16 are secured to the gib above the grooved bar on opposite sides 90 of the center of the gib, thus leaving a crosswise travel-space for the slide-plate 4. The upper part 18 of the slide-rest is recessed circularly immediately above the gib, as shown at 18^b in Fig. 14, and is also recessed circularly in 95 its upper surface, as shown at 18^c, is bored centrally of the recesses, as shown at 18^d, and is slotted, as shown at 18^e. A two-part dial-plate is used to control the inclination of the pivoted slide-key 6, and this dial-plate is secured to part 18 of the slide-rest, with the groove 8 receiving the key. The upper member 10 of the dial-plate occupies recess 18^c and the lower member 7 occupies recess 18^b. A pivot extension 9 is formed on the upper 100 surface of member 7, and it pivots in bore 18^d.

The extension 9 is bored and internally threaded, and the upper member 10 has an externally-threaded extension 12, which screws into pivot extension 9. A wrench-seat 11 is formed on the upper surface of member 10, and a screw 13 extends through a hole in the upper member, extends through slot 18° in the slide-rest member, and screws into the lower dial-plate member 7. The dial-plate members are bored centrally, as shown in Fig. 15, to provide an oil-passage leading to the slide-keys.

The upper part of the dial-plate is suitably graduated, as suggested in the drawings, and the screw 13 holds the groove in the lower part of the dial-plate in proper relation to the gradations. The screw 13 also prevents the dial-plate from swinging slide-key 6 into an inoperative position by striking sides of slot 18°, and it is used to clamp the parts of the plate onto the slide-rest, with the groove 8 extending in any desired direction.

When the dial-plate is fastened in the position shown in Fig. 12, the pivoting slide-key 6 will be held at right angles with the slotted bar 1, and the device will be inoperative or passive as an accelerator or retarder. When the dial-plate is adjusted to the position shown in Figs. 10 and 11, the slide-key 6 will be swung to the position shown in Figs. 4 and 5, and under these conditions the upper part 18 of the slide-rest will advance with relation to the under part 14 to the extent shown in Figs. 10 and 11 as the tool-carriage 35 is moved from one end of its slideway to the other. By turning the dial-plate in the contrary direction the slide-key 6 will be inclined, as shown in Fig. 8, and the tool-carrying part of the slide-rest will be retarded to an extent 40 equal to the advance shown in Figs. 10 and 11. In the conditions above mentioned the set-screw 13 is supposed to be swung to one end or the other of slot 18° or to be located at the center of the slot; but the dial-plate may 45 be adjusted in various intermediary positions and the cutting-tool be accelerated or retarded to any required degree.

As the slide-rest moves along the grooved bar 1 the slide-key 3 follows the inclination 50 of groove 2 and moves plate 4 crosswise of the slide-rest or crosswise of the direction of the motion thereof. The slide-key 6 travels with the plate 4 across the slide-rest, and when it is set obliquely it forms an inclined 55 plane to convert its crosswise motion into independent motion of part 18 of the slide-rest lengthwise of the slotted bar. The motion of part 18 with relation to part 14 is used to retard or accelerate the tool-post 17 60 and the tool therein, as hereinbefore explained.

When the tool has completed a cut, the slide-rest may be moved on the cross-slide of the carriage in the customary manner, and

the slotted bar 1 will slide on bar 19 to permit this movement.

The set-screw 13 is loosened preparatory to adjusting the dial-plate, the plate is turned to the required position by means of a wrench applied to seat 11, and the set-screw 70 is retightened.

I claim as new and desire to secure by Letters Patent—

1. In a screw-cutting lathe, the combination of a slide-rest member attached to the carriage, a second slide-rest member movable on the first lengthwise of the lathe and carrying a screw-cutting tool, a plate in the first slide-rest member slidable crosswise thereof, a bar extended along the line of travel 80 of the slide-rest and provided with an oblique groove, a slide-key fixed on the plate in engagement with the oblique groove, a slide-key pivoted on the plate, and an adjustable dial-plate on the tool-carrying member of 85 the slide-rest having a groove in which the pivoted slide-key slides.

2. In a screw-cutting lathe, the combination of a slide-rest member attached to the carriage, a second slide-rest member movable on the first lengthwise of the lathe and carrying a screw-cutting tool, a plate on the first slide-rest member slidable crosswise thereof, a bar attached to the tail-stock crosswise of the lathe, a flat bar grooved crosswise of one of its ends to slidably engage the bar on the tail-stock, and also having a groove extending obliquely along its length, a fixed slide-key on the cross-plate engaging the oblique slot of the slotted bar, a slide-key pivoted on the cross-plate, and an adjustable dial-plate on the tool-carrying member of 95 the slide-rest, having a groove in which the pivoted slide-key slides.

3. In a screw-cutting lathe, the combination of a slide-rest member attached to the carriage and having a gib on its upper surface extended lengthwise of the lathe, a bar fitted slidably in the gib lengthwise thereof, said bar being provided with an oblique 100 groove in its upper surface and held against lengthwise motion, a tool-carrying slide-rest member mounted slidably lengthwise of the lathe on the gibbed member, a plate having motion in the tool-rest crosswise of the travel 115 thereof, a slide-key fixed on the under side of the cross-plate in engagement with the slot of the bar, a slide-key pivoted on the cross-plate, a grooved dial-plate engaging the pivoted slide-key, and means for holding the dial-plate in various positions.

In testimony whereof I sign my name in the presence of two subscribing witnesses.

ANTON SCHUERMANN.
